WITNES:

UNITED STATES PATENT OFFICE.

NELS B. ANDERSON, OF HAWLEY, MINNESOTA.

RUNNER ATTACHMENT FOR SKATES.

Application filed March 26, 1927. Serial No. 178,782.

This invention relates to runner attachments for skates embodying among other characteristics a pocket for receiving skate runners.

5 Another object of the invention comprehends retaining elements adapted for engagement with the skate.

A further object contemplates a runner member carried by the retaining elements.

10 With the above and other objects in view, the invention further consists of the following novel features and details of construction to be hereinafter more fully described, illustrated in the accompanying drawing, 15 and pointed out in the appended claims.

In the drawing:

Figure 1 is a side elevation of the invention applied and partly broken away to illustrate the relative arrangement of the 20 attachment and skate runners.

Figures 2, 3 and 4 are sectional views taken on lines 2-2, 3-3 and 4-4, respectively, upon Figure 1 of the drawing.

Figure 1 illustrates a conventional form 25 of skate runner and referring more specifically to details of construction the reference character 10 indicates a tubular body portion supporting a runner 11 therefrom. Said body portion is provided with standards 12 supporting shoe plates 13 upon which shoes may be attached.

The invention comprehends a channel portion 14 adapted to receive the skate runner 11 and to support the same upon a cushion seat 15 to protect the sharpened edges thereof. Curved gripping portions 16 disposed upon the upper edges of the channel portions 14 are adapted to engage the outer sides of the tubular body portion 10 of the 40 skate. Cut-out portions 17 are provided at appropriate intervals in the upper edges of the gripping portions 16 to permit appreciable portions of the standards 12 to be inserted therein and to check independent 45 sliding movement of the body portion between the gripping portions 16.

A runner 18 carried by the channel portion 14 is concaved upon the underside thereof to dispose the side edges thereof in position for effective engagement with a surface 50 to permit turning and to obviate skidding. The channel portion 14 and gripping portions 16 are provided with reinforcing fins 19 adapted to engage the upper sides of runners 18 to preserve the contour of the 55 runner 18.

The runner attachment is adapted for use upon the conventional form of skates which will enable a skater to effectively use the skates upon snow covered rinks and upon 60 crusted snow.

The invention is susceptible of various changes in its form, proportions and minor details of construction, and the right is herein reserved to make such changes as 65 properly fall within the scope of the appended claims.

Having described the invention what is claimed is:

1. A runner attachment for skates comprising a channel portion adapted to receive the skate runner, curved gripping members carried by the channel portions adapted for frictional engagement with the skate body, and a runner carried by the channel portion 70 being concaved for the major portion of its length.

2. A runner attachment for skates comprising a channel portion adapted to receive the skate runner, curved gripping members 80 carried by the channel portions adapted for frictional engagement with the skate body, a runner carried by the channel portion being concaved for the major portion of its length, and reinforcing fins carried by the 85 gripping portions and channel portion to preserve the contour of the runner.

In testimony whereof I affix my signature.

NELS B. ANDERSON.
